WALTER S. LEVIN, OF SAN FRANCISCO, CALIFORNIA, ASSIGNOR TO THE NATIONAL SAFETY APPLIANCE COMPANY, OF SAN FRANCISCO, CALIFORNIA, A CORPORATION OF CALIFORNIA.

AUTOMATIC TRAIN SIGNAL AND STOP.

1,305,380.

Specification of Letters Patent. Patented June 3, 1919.

Application filed April 24, 1915. Serial No. 23,587.

To all whom it may concern:

Be it known that I, WALTER S. LEVIN, a citizen of the United States, and a resident of San Francisco, county of San Francisco, 5 State of California, have invented certain new and useful Improvements in Automatic Train Signals and Stops, of which the following is a specification.

The objects of the invention will fully appear to one skilled in the art from the hereinafter description taken in connection with the accompanying drawings in which the same reference character indicates the same part in the several views.

15 Figure 1 of the drawing is a diagrammatic view of certain features of the invention used in signaling.

Fig. 2 is a diagrammatic view of the invention as used in signaling and train stopping, certain of the parts being shown in different positions than shown in Fig. 1.

Fig. 3 is a side elevation, certain parts being broken away, of a track, the cab and part of a locomotive and tender showing the 25 invention applied thereto.

Fig. 4 is an elevation of a casing mounted in the cab of the engine containing certain parts of the signaling and train stopping mechanism.

30 Fig. 5 is a top plan view of certain parts of the apparatus viewed on line 5 of Fig. 3.

Fig. 6 is a side elevation partly in section of the train magnet.

Fig. 7 is a cross section of the same on 35 line 7 of Fig. 6.

On the drawing the part marked A represents a railway track or roadbed, B part of a locomotive, B' the cab thereof, C the tender and C' a truck under the tender.

40 Signals are transmitted to the cab by means of a series of powerful electro-magnets 10 located longitudinally of the track in staggered relation to each other between the rails. The means for controlling the operation of the magnet are not shown in detail but the windings of the magnet are illustrated as connected by conducting wires 11 and 12 to a battery 13 by which the magnet is energized.

45 In the construction of this magnet, as shown, the ends of the core 10^a extend beyond the winding or spool and are provided with the pole pieces 10^b, the upper ends of each of these pole pieces being widened or enlarged as more clearly shown in

Fig. 7 of the drawing. The magnet may be 55 inclosed in a casing 14 provided with a cover 15, having downwardly turned ends 16 to secure a tight joint. To the casing is secured L-shaped brackets 17 by which the magnet or its casing is fastened to the cross ties of the roadbed. To prevent the magnet from being injured by any of the gear of the train a shoe 20, which may be made of wood or other suitable material, beveled or inclined upwardly toward the magnet, is placed at each 60 end of the magnet as shown, and the end of the shoe next to the magnet may be reinforced with a piece of angle iron 21. Secured beneath the tender of the engine and preferably to the truck thereof is a cross bar 22, to which is bolted a set of four induction magnets 25. These magnets are located on this cross bar in pairs toward the rails leaving a sufficient space at the center to prevent interference by any of the equipment of the 65 track or running gear of the train. The magnets 10 are so located on the track that a corresponding magnet 25 will pass directly over it when the train is moving and the cross bar is so located that the magnets 25 70 will be a suitable distance above the magnets 10, about three inches as now constructed. Each of the magnets 25 is of special construction and consist of two coils 26 wound in the form of circular bobbins, an iron core 27 projecting through the bobbins and provided with extended pole pieces 28 and an iron bar 30 secured to an end of each core. The coils are connected by conductors 31 75 which may pass through a piece of pipe to protect the same, the ends of the pipe being secured to the bobbins. Leading from the coils or bobbins are the conductors 32 and 33 which connect the coils in series with a relay 34 and a battery 35, the said coils and the coils of the relay being of relatively high resistance, and as the voltage of the battery supplying the coils is 2.8, only a small amount of current is necessary to hold the armature 34^a in its normally closed position. 80 Although the amount of current consumed by the relay is comparatively small, the magnet is sufficiently powerful to prevent the contacts from accidentally opening by vibration or jar of traffic conditions.

85 Located in the cab of the engine is a casing 40 in which are four electro-magnetic controlled air valves 45, three for controlling

the lamp signals 71 and signal whistles 44, and the fourth for controlling the vent of the automatic brake mechanism as well as a signal whistle. A set of lamp signals is placed in the front and rear of the cab so that the signals may be observed by the engine driver when the engine is moving either backward or forward. The valve and controlling apparatus are alike and a description of one will answer for all.

41 is a valve casing which is connected to the air supply pipe 42. 43 is another air pipe leading from the casing and to which is attached the signal whistle 44. 45 is a valve in the casing to control the supply of air thereto. 46 is a lever connected to the casing and contacts with the stem of the valve to hold the valve to its seat. 50 is a magnet to control the valve 45 and it is so constructed that it cannot attract its armature 51 after the circuit has been broken but the armature must be manually restored. To accomplish this the armature is provided with a stem 53 which projects through an opening 54 in the end of the lever. Secured to the stem is a plate or disk 55 and surrounding the stem below this disk is a coil spring 56, the lower end of the spring bearing against another disk 57 loose on the armature stem, the spring forcing the latter disk into engagement with the lever 46. The outer end of the armature stem is provided with a depressing knob 58. The magnet is connected in series with a contact or armature 34^a of the relay 34 and to the battery 35 through the wires 60, 32 and 61, the same battery being used for supplying current for the receiving coil of the induction magnets, relays, valves and lamps. 70 is a spring contact to one member 70^a of which is connected the conducting wire 61^a, and in this wire is the signal lamp 71. The other member 70^b of the spring contact is connected to a conducting wire 63 which leads to the battery 35 through the wire 42. All of the wires from the induction magnets may be placed in a cable 75 which extends under the tender and up through the cab to the box 40. This cable is provided at suitable places with connecting plugs 76 and 77 so that the cable can be readily broken or detached.

The operation of the device is as follows: When the locomotive is traveling along the track and one of the track magnets 10 is properly energized, to cause a signal or to stop the train, as the corresponding induction magnet 25 passes through the field of the track magnet a current is generated by induction in the said magnet 25 which is more powerful than and flows in the opposite direction to the battery current normally flowing in the coils 26 of the said induction magnet. The action of the induced current in the coils 26 momentarily reverses the magnetism of the relay 34 and permits

the armature 34^a thereof to drop, thus breaking the circuit of the cab apparatus. Only a momentary operation of the relay is necessary to properly transmit a signal or cause the stopping mechanism to be operated. The cab apparatus has to be manually restored to normal position after the relay has opened its contact for an extremely brief interval. The battery current is used through the induction coil to give protection against the loosening or breaking of any wire or connection, and while not essential to the actual operation of the apparatus, it is absolutely necessary to guard against any accident to wires and so forth. This interruption of the circuit momentarily deenergizes the magnet 50 and releases the armature 51, whereupon the pressure of air in the supply pipe 42 unseats the valve 45, whereupon the air rushes through the valve casing 41 into the pipe 43 and blows the whistle 44. When the valve is unseated the lever 46 is raised and the spring 56, which is normally under a slight pressure, is further compressed causing the disk 55 to press the contact member 70^b against the contact member 70^a, closing the lamp circuit. The construction is such that the action of the spring when the armature is released will not force the disk 55 to close the lamp circuit unless the lever is lifted high enough by the valve 45 to give the spring additional pressure. The object of this is to economize battery current by preventing the lamp from burning when the engine is in the round house and all the valves are released by reason of the reversing switch being in the "off" position. To restore the armature, the knob 58 is depressed. This forces the armature 51 into contact with the coil 50, which being energized, having been only momentarily deenergized upon the release of the armature 34^a, holds the armature down to its normal position. When the armature is forced to its normal position the disk 55 moves out of contact with the spring member 70^b which moves to normal position, opening the lamp circuit. As the knob is pressed downward the lever 46 seats the valve and cuts off the supply of air to the signal whistle, the magnet through its armature holding the lever down so that the valve cannot be released. The valve controlling the automatic stop mechanism operates in the same manner as in the signal apparatus, the only difference in construction being that the pipe 43 leads to an automatic valve 80 which operates to reduce the pressure in the train pipe 81 which causes the brakes to be applied in the usual manner, and the whistle 44^a is connected to be operated by the air flowing through pipe 43, as more fully shown in Fig. 2. The automatic valve 80 must be reset by the engineer leaving the cab before the brakes can be released.

Various changes may be made in certain

details of the apparatus without departing from the spirit of the same and it may be here stated that a polarized relay will respond correctly to the current generated in the induction magnet, but the simpler form shown and described in detail is preferable as it is cheaper to manufacture and it is found to be perfectly reliable.

It is also apparent that as the current normally continuously flows through the various circuits, any interruption of the current from any cause will deenergize the magnet 50 and cause a visible and audible alarm to be given.

15 What I claim as new and desire to secure by Letters Patent, is:—

1. In a train signaling and stopping apparatus, a single magnet secured to the road bed, a single induction magnet carried by the train, a normally closed relay connected to the said induction magnet, a signaling and stopping device, a magnet connected to the relay to control the signaling and stopping device, said magnet being normally energized, said parts being operated when the road bed magnet is energized and while the induction magnet is passing through the field of the road bed magnet to produce a current of greater strength than the normal relay current.

2. In a train signaling and stopping apparatus, a magnet secured to the road bed, an induction magnet carried by the train, a normally closed relay connected to the induction magnet, a separate circuit for said relay, a stopping device and an audible signal, a magnet connected to the relay circuit and controlling the stopping device and the audible signal, said parts being operated when the road bed magnet is energized and while the induction magnet is passing through the field of the road bed magnet to produce a current of greater strength than the normal current of the separate relay circuit, a visual signal, and means controlled by the stopping device magnet for operating the visual signal.

3. In a combined train signaling and stopping apparatus, a single magnet secured on the roadbed, a single magnet carried by the train and movable within the field of the track magnet whereby induced currents of greater strength than normal are produced in the train magnet, a valve, a signaling and stopping device controlled by the said valve, means for normally holding the said valve closed and means to release the valve when said induced current is produced in the train magnet.

60 4. A combined train signaling and stopping apparatus, a magnet secured to the road bed, a single magnet carried by the train and movable within the field of the track magnet whereby induced currents are produced in the train magnet, a valve, a signaling and

stopping device controlled by the said valve, means for normally holding the said valve closed and means to release the valve when said induced current is produced in the single train magnet.

70

5. In a train signaling and stopping apparatus, a single magnet secured on the roadbed, a single magnet carried by the train and movable within the field of the roadbed magnet whereby induced currents are produced in the train magnet, a normally closed relay connected to the winding of the train magnet, a valve casing, an air supply pipe connected to the casing, an air outlet pipe leading from the casing, a signal whistle connected to the outlet pipe, a valve in the casing controlling the supply of air and means for releasing the valve from its seat, said means including a magnet connected to the relay circuit.

85

6. In a train signaling and stopping apparatus, a single magnet secured on the roadbed, a single magnet carried by the train and movable within the field of a roadbed magnet whereby induced currents are produced in the train magnet, a normally closed relay connected to the winding of the train magnet, a valve casing, an air supply pipe connected to the casing and an air outlet pipe leading from the casing, a signal whistle connected to the outlet pipe, a valve in the casing controlling the supply of air, means for releasing the valve from its seat, said means including a normally energized magnet connected to the relay circuit and means for manually reseating the valve and means for causing the last named magnet to hold the valve to its seat.

95

7. In a train signaling and stopping apparatus, a single magnet secured on the roadbed, a single magnet carried by the train and movable within the field of the track magnet whereby currents are induced in the train magnet when the track magnet is energized, a normally energized relay connected to the windings of the train magnet, a valve casing, an air supply pipe connected to said casing, a signal whistle connected to said casing, a valve in the casing adapted to open and close the air supply pipe, a lever for holding the valve to its seat, a magnet having an armature with a stem thereon, the said lever being connected to the armature, a circuit connecting the magnet and the relay, a contact in the circuit adapted to be operated on the movement of the armature.

105

8. In a train signaling and stopping apparatus, a single magnet secured on the roadbed, a single magnet carried by the train and movable within the field of the track magnet whereby currents are induced in the train magnet when the track magnet is energized, a normally energized relay connected to the windings of the train mag-

115

net, a valve casing, an air supply pipe connected to said casing, a signal whistle connected to said casing, a valve in the casing adapted to open and close the air supply pipe, a lever for holding the valve to its seat, a normally energized magnet having an armature with a stem thereon, said lever being connected to the armature, a circuit connecting the magnet and relay, a signal lamp in the circuit and a contact in the circuit adapted to be operated on the movement of the armature.

9. In a train signaling and stopping apparatus a single magnet secured on the roadbed, a single magnet carried by the train and movable within the field of the track magnet whereby currents are induced in the train magnet when the track magnet is energized, a normally energized relay connected to the windings of the train magnet, a valve casing, an air supply pipe connected to said casing, a signal whistle connected to said casing, a signal whistle and a train stop valve operated by air passing through the casing, a valve in the casing adapted to open and close the air supply pipe, a lever for holding the valve to its seat, a normally energized magnet having an armature with a stem thereon, said lever being connected to the armature, a circuit

connecting the magnet and relay, a signal lamp in the circuit and a contact in the circuit adapted to be operated on the movement of the armature.

10. In a train signaling and stopping apparatus, a magnet consisting of a circular bobbin, a core passing through the bobbin, field pieces connected to an end of each core, said field pieces being widened or enlarged at their upper or free ends, a casing to receive the magnet, said casing having a cover provided with downwardly turned ends and brackets secured to the casing to secure the magnet to the track and deflecting protectors for said magnet. 35

11. In a train signaling and stopping apparatus, a magnet secured to the roadbed, deflecting protectors also secured to the roadbed and situated adjacent to and independent of the magnet, and arranged 40 longitudinally of the roadbed.

In witness whereof I have hereunto set my hand at San Francisco, county of San Francisco, State of California, this 19th day of April, 1915.

WALTER S. LEVIN.

In presence of—

S. A. BOSTNICK,
GEORGE C. FAULKNER.
